UNITED STATES PATENT OFFICE.

JOHN M. SPITLER, OF CABLE, WISCONSIN.

FARM-GATE.

1,074,477.

Specification of Letters Patent. Patented Sept. 30, 1913.

Application filed January 23, 1913. Serial No. 743,820.

To all whom it may concern:

Be it known that I, JOHN M. SPITLER, a citizen of the United States, residing at Cable, in the county of Bayfield and State 5 of Wisconsin, have invented certain new and useful Improvements in Farm-Gates; and I do hereby declare the following to be a full, clear, and exact description of the invention, such as will enable others skilled 10 in the art to which it appertains to make and use the same.

This invention relates to gates and particularly to farm gates.

The object of the invention is to generally 15 improve the construction and operation of this class of gates by providing an improved gate which may be swung from a post at one end of a bracket, or inverted on a horizontal pivot at its middle, or swung upon a vertical pivot at its middle, the arrangement being such that the gate may be raised horizontally from the ground, and opened or closed by operating it upon any of the specified pivots.

25 With this object in view the invention consists of an improved construction, arrangement and combination of parts of a gate, which will be hereinafter fully described and afterward specifically claimed.

30 In the accompanying drawings which illustrate an approved embodiment of my invention, and in which,

Figure 1 represents the side elevation, Fig. 2 a top plan view, Fig. 3 a similar view 35 with the gate in a partly opened condition shown in dotted lines, and Fig. 4 a fragmentary sectional view on the plane indicated by the broken line 4-4 of Fig. 1.

In these drawings, in which similar reference characters correspond to similar parts throughout the several views, my improved gate consists of stationary posts 5 and 6, a vertical and rotatable post 7, a substantially horizontal supporting beam or arm 8, an 45 adjustable supporting element or link 9, a pivot support 10 and the gate proper or closure element 11. The rotatable post 7 is provided with pivots 12 and 13, the former being journaled in the support 10, and the 50 latter pivot being journaled in a cap or bearing block 14 which is secured on top of the post 5. At the middle portion of the gate member 11 is a pair of vertical battens 15, and through these battens extends a bolt 55 16 having screw threaded engagement with a hinge member 17 and being provided with

a nut 18 whereby it is locked securely and firmly united with said hinge member, so as to form a pivot on which the gate member 11 is supported. This hinge member 17 is 60 supported on the free end of the supporting arm or beam 8, being pivotally connected thereto by means of a bolt 19. A brace 20 engages with the upper end of the bolt 19, and is secured firmly on the supporting beam 65 8 by means of bolts 21 and 22. The bolt 21 is formed with an eye which is engaged with the end of the link 9, said link having its other end engaged with an anchor member 23 which is secured to the post 7. The 70 link 9 comprises two lengths of screw threaded rod having right and left threads, respectively, and being engaged by an internally screw threaded element 24, so as to form a turnbuckle, whereby the length of 75 the link may be increased or reduced at will. The post 7 is provided with an aperture 7' in which an end of the beam 8 is fitted, while a pivot-pin 26 extends through said post and said beam, so that the free end of the beam 80 may be raised and lowered, alternately, by means of the turnbuckle.

The gate post 7 is provided with latch elements 27, while similar latch elements are provided on the post 6; said latch elements 85 being of the ordinary type in which the top is notched and the free end is inclined. However, this latch element differs from the ordinary kind by being secured to the post at its medial portion, and having its end 90 portions extending laterally and equally beyond the sides of the post. In the present form of construction, I preferably secure one of the latch members 27 on a lower plane than the other of said latch members, although I do not confine my invention to this particular relation of parts.

In practice, the ends of the gate panels 11' are seated in the respective notches of the latch members 27, while the turnbuckle 100 is so adjusted that it would support the gate approximately on the same level if the latch members were removed; and so, the weight of the gate is supported by the latch members, thereby preventing a constant lateral 105 strain on the posts 5 and 7. When it is desired to operate the gate, either end of the closure 11 may be raised out of engagement with the latch member 27 which supports it, and then, by pressing down on the released end, the other end is forced upward 110 and released from the other latch member;

it being understood that there is sufficient looseness or play in the pivotal connection at the middle of the gate to allow the foregoing movement. When the closure has thus 5 been released, it may then be swung upon the pivot 19, while also being swung upon the pivots 12 and 13, so that the closure may be caused to pass through the gate-way between the posts 6 and 7, and so it may be 10 disposed in the closed position shown in Fig. 3, wherein the ends of the gate are on opposite sides of the posts 6 and 7. When in this position, the closure 11 may be swung on its pivot 19, as indicated by dotted lines, 15 independently of pivots 12 and 13, through approximately 180 degrees, so that the ends of the closure change places with respect to the posts 6 and 7, but on opposite sides thereof and in engagement with the other 20 notches of the respective latch members 27. While being thus swung on the pivot 19, the closure 11 is balanced on its middle pivot, and therefore the friction is greatly reduced, so that the ease of operation is 25 greatly increased, as compared with gates of ordinary construction. Now, assuming that a pedestrian approaches the gate in the direction of the arrow (see Fig. 3), it will be seen that it is not essential for him to walk 30 throughout the length of the gate, so as to open the same; but he may raise the near end of the gate out of engagement with the member 27, and may pass between the closure 11 and post 7 and then either step 35 over or duck under the beam 8; or else he may swing the gate on its pivot 19, as in broken lines, until the position is reversed, and he may walk through the gateway adjacent to the pivot 19 while the closure is 40 thus being reversed, thereby saving several steps, and perhaps avoiding a mud-hole or puddle, such as frequently occurs within gateways.

In case of deep snow, the turnbuckle 24 45 may be operated so as to raise the entire closure 11 sufficiently to avoid the contact of the gate with this impediment, and similarly, the closure may be raised for allowing small animals to pass thereunder, as 50 previously mentioned. It may sometimes be desirable that large hogs or calves may pass under the gate, while horses and large cattle are barred, and in such case, the gate

may be released from its central connection with the beam 8 and inverted, so that, obviously, the space under the gate would be 55 greatly increased.

It will be seen that I have provided a gate of this character which is fully capable of attaining the foregoing objects, in a thoroughly practical and efficient manner. 60

I do not limit my invention to the exact details of construction, combination and arrangement of parts, as herewith illustrated and described, but my invention may only 65 be limited by a reasonable interpretation of the claims.

I claim:

1. The combination with a pair of rigid posts and a post mounted to swivel on its vertical axis, of a substantially horizontal swinging supporting arm pivoted to the swiveled post, a gate proper, a bracket attached centrally to the gate on a horizontal pivot and resting on the end of the supporting arm, a vertical pivot in said bracket passing also through the supporting arm, and a main brace comprising a threaded rod attached to the arm, a like rod attached to the swiveled post, and a turnbuckle connecting the threaded rods. 70 75 80

2. The combination with a pair of rigid posts and a post mounted to swivel on its vertical axis, of a substantially horizontal swinging supporting arm pivoted to the swiveled post, a gate proper, a bracket attached centrally to the gate on a horizontal pivot and resting on the end of the supporting arm, a brace having one end resting on top of said bracket and the other end on top of the swinging arm, a vertical pivot in said bracket passing also through the supporting arm and brace, a plain bolt securing the brace to the arm, an eye-bolt passing through the arm and brace and projecting above the latter, and a main brace connecting the eye-bolt with the swiveled post and comprising a turnbuckle. 85 90 95

In testimony whereof I have signed my name to this specification in the presence of 100 two subscribing witnesses.

JOHN M. SPITLER.
